Arthur B. Jenkins,
ATTORNEY

UNITED STATES PATENT OFFICE

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT

SUIT CASE LOCK

Application filed June 22, 1928. Serial No. 287,444.

My invention relates to the class of locks particularly applicable for securing the cover of a suitcase, trunk or like receptacle in a closed position, and an object of my invention, among others, is to so construct the lock that there shall be little liability to injury by blows accidentally delivered; and a further object of the invention is the provision of a lock that shall be strong and durable and particularly efficient in operation.

One form of lock embodying my invention and in the construction and use of which the objects herein set out, as well as others, may be attained, is illustrated in the accompanying drawings, in which—

Figure 1 is a face view of my improved lock.

Figure 2 is a similar view but with parts broken away to show the construction, the plane of section of the lock casing being denoted by the dotted line 2—2 of Figure 3.

Figure 3 is an edge view.

Figure 4 is a view in section on the plane denoted by the dotted line 4—4 of Figure 1.

Figure 5 is a view in section on a plane denoted by the dotted line 5—5 of Figure 1.

While my invention is not limited in its use to a lock designed for any particular purpose, yet as it finds ready adaptation to use in connection with a suit case lock, such has been selected by me for the purpose of disclosing my invention herein.

In many of the locks heretofore constructed a hasp has been employed that in its open position is projected outwardly and in its closed position projects to such extent that injury is liable to be caused from blows delivered by contact of the casing bearing the lock with obstacles or by forcible contact of such obstacles with said casing. It is my purpose to overcome these conditions by so constructing a lock that there shall be no parts that will project unduly and, therefore, be liable to injury from the causes above mentioned, such a lock being shown in the accom-

panying drawings in which the numeral 6 indicates a lock casing having a chamber closed in any suitable manner to house the lock mechanism. An opening 7 is formed in one edge of the casing to receive a bolt 8 projecting from a hasp 9. This bolt has a cam edge to engage with the edge of the opening 7 and thereby draw the cover of the suit case into tight engagement with the body thereof. The hasp 9 is pivotally attached to a support 10 adapted to be secured to the lid of a suitcase or trunk in any suitable manner, and a spring 11 may be employed to throw the hasp to its open position, and as indicated in dotted lines in Figure 1 of the drawings.

A latch lever or keeper 12 is pivotally mounted in the case 6, one end of this lever having a nose to engage the bolt 8 to hold the hasp 9 in its closed position, the other end of this latch lever or keeper projecting through a hole in edge of the casing 6 and having a thumb piece 13 located outside of the casing and by means of which said keeper is operated to release the bolt 8. This keeper is forced to its locking position as by means of a spring 14, and as shown in Figure 2 of the drawings.

A dog plate 15 is slidably mounted in the case 6 and has a dog 16 adapted to engage, in one position, a lug 17 on the edge of the lever or keeper 12 to hold it in its locked position when said dog 16 is located opposite said lug in the sliding movement of the plate 15. A guide stud 18 projects from a wall of the casing 6 into a slot in the plate 15 and a locking stud 19 projects from the plate 15 into a notch in a tumbler 20 pivotally mounted in the casing to control operations of the plate 15. The tumbler 20 and the plate 15 are actuated in a manner that will be readily understood as by means of a key inserted through a key hole 21. The plate 15 and the tumbler 20, so far as the construction of the parts to be engaged and actuated by the key are concerned, are of old and well known

construction and will be readily understood by those skilled in the art. The hasp 9 is so arranged with respect to the support 10 and the lock casing 6 that it lies below the outer face of said parts, that is, contiguous to the edges thereof so that it is shielded by said support and case from forcible contact with objects that might tend to injure it. In fact, its pivoted end is housed within the support 10 and its opposite end is provided with a finger hold 22 for use in closing the hasp.

It will be noted that with this arrangement after a key has been used to release the keeper 12 the thumb piece 13 may be operated to move said keeper and release the bolt 8, whereupon the hasp 9 will swing to its open position, as denoted in dotted lines in Figure 1 under the influence of the spring 11. It will further be noted that in this operation the fingers of the operator will be located on the cover of the suitcase while the thumb is used to operate the thumb piece 13, the fingers thus being in position to open the cover of the suit case and without changing the position of the hands.

A material advantage is derived in the use of my improved lock in that when the hasp is in a position in line with its support 10, as shown in dotted lines in Fig. 1, such hasp will lie against the edge of the suitcase cover and will therefore present no obstruction upon which garments may catch, as would be the case if the hasp projected on either side of the cover, and garments may therefore be readily laid over the edge of the cover without danger of injury thereto.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A lock including a lock casing having an opening in its side edge, a keeper within said casing, means for operating said keeper, a hasp support, a hasp pivotally attached at one end to said support and adapted to project along said side edge of said lock casing for substantially the full width thereof to constitute a shield therefor, and a bolt secured to and spaced from the end of said hasp to enter said opening and engage said keeper.

2. A lock including a lock casing having an opening in its side edge, a keeper within said casing, means for operating said keeper, a hasp support, a hasp pivotally attached at one end to said support and adapted to project along said side edge of said lock casing for substantially the full width thereof to

constitute a shield therefor, a bolt secured to and spaced from the end of said hasp to enter said opening and engage said keeper, said hasp moving in the plane of the casing and support from a position extending across the 70 casing when in locked condition to an unlocked position at right angles to the locked position, and means on the support for limiting opening movement of the hasp.

ELMER B. STONE.
